UNITED STATES PATENT OFFICE.

SYLVESTER MUNSON, OF JOLIET, ILLINOIS.

IMPROVEMENT IN DAMPERS.

Specification forming part of Letters Patent No. 41,636, dated February 16, 1864.

To all whom it may concern:

Be it known that I, SYLVESTER MUNSON, of Joliet, in the county of Will and State of Illinois, have invented a new and Improved Heat and Draft Regulating Valve for Stove-Pipes; and I do hereby declare the following to be a full and exact description of the same, reference being had to the accompanying drawings, making part of this specification, in which—

Figure 1 is a plan or top view of my invention, shown in position for closing or shutting off the draft. Fig. 2 is a similar view thereof, showing the draft open. Fig. 3 is a sectional elevation of the same in the line $x x$ of Fig. 1, illustrating the application of the same to a stove-pipe.

Similar letters of reference indicate corresponding parts in the several views.

The object of this invention is to obtain a valve or damper whereby the draft in stoves may be regulated at will with great facility, and the invention consists in the combination of two semicircular or nearly semicircular slotted plates, adapted to slide one upon the other for the purpose of opening and closing the draft, or to be turned in the stove-pipe to effect this object, as will be hereinafter explained.

In order that others skilled in the art to which my invention appertains may be enabled to fully understand and use the same, I will proceed to describe its construction and operation.

In the accompanying drawings, $a a'$ may represent two semicircular plates, adapted to slide one upon the other and connected and guided by pins $e e$, which move in slots $d d$, formed in the plates. Each plate is provided with an oblong rectangular opening, c , which openings are designed to be placed directly

over or in communication with each other when the draft is to be opened, or each of the said openings to be closed by a portion of the plate in which the other opening is made, in the manner to be described. The respective plates $a a'$ are supported within the pipe A by pivots or pins $b b'$, the latter of which ends in a handle, b^2 by which the valve may be operated as required.

The plates $a a'$ are so constructed that when the handle b^2 is drawn outward to its fullest extent the said plates will completely close the pipe, prevent the existence of a draft, and retain the heated air within the stove—that is to say, when the plates are arranged horizontally within the pipe. The plates may be so fixed within the pipe that they will remain in a horizontal position when thus placed, but be adapted to turn therein upon the pins $b b'$ and remain in a vertical position in order to create a stronger draft of air, but in common the plates may be allowed to remain in a horizontal position and sufficient draft obtained by placing the openings c one above the other by pushing in the handle b^2 .

This invention is simple, may be readily modified to conform to the shape of any pipe, and with it the required functions may be performed in a most efficient and facile manner.

Having thus described my invention, what I claim as new therein, and desire to secure by Letters Patent, is—

The damper or valve herein described and represented, composed of two plates, a and a' , arranged in relation to each other so as to operate in the manner and for the purpose set forth.

SYLVESTER MUNSON.
